UNITED STATES PATENT OFFICE.

WILLIAM A. SNOW, OF WINCHESTER, MASSACHUSETTS.

DESIGN FOR A BENCH.

Application filed August 17, 1925. Serial No. 14,496. Term of patent 14 years.

To all whom it may concern:

Be it known that I, WILLIAM A. SNOW, a citizen of the United States, residing at Winchester, in the county of Middlesex and State of Massachusetts, have invented a new, original, and ornamental Design for a Bench, of which the following is a specification, reference being had to the accompanying drawing, forming a part thereof.

The figure of the drawing is a perspective view of a bench showing my new design.

I claim:

The ornamental design for a bench as shown.

WILLIAM A. SNOW.
